UNITED STATES PATENT OFFICE

155,073

DESIGN FOR A GLASS BOTTLE

Reginald Malcolm Broadhead, London, England,
assignor to Lifeguard Products Limited, London, England, a company of Great Britain

Application May 3, 1948, Serial No. 146,147

Term of patent 14 years

(Cl. D58—8)

To all whom it may concern:

Be it known that I, Reginald Malcolm Broadhead, a subject of the King of Great Britain, Northern Ireland and the Isle of Man, residing at 1 Queen Victoria Street, in the county of London, England, have invented a new, original, and ornamental Design for a Glass Bottle, of which the following is a specification, reference being made to the accompanying drawing, forming part thereof.

I claim:

The ornamental design for a glass bottle, as shown.

REGINALD MALCOLM BROADHEAD.
